OPERATOR FOR WINDOWS, VENTILATORS,
AND THE LIKEClaude J. Teggelaar and Michael N. Swierbut, Grand
Rapids, Mich., assignors to Grand Rapids Hardware
Company, Grand Rapids, Mich.Filed May 6, 1957, Ser. No. 657,428
4 Claims. (Cl. 268—105)

This invention relates to an operator for swingably mounted windows, ventilators, and the like. The main objects of this invention are,

First, to provide an operator for swingable windows, ventilators, and the like which is relatively simple in structure and may be compactly collapsed.

Second, to provide an operator for windows, ventilators, and the like which may be merchandised and easily installed as a unit.

Third, to provide an operator having these advantages, most parts of which may be formed as stampings and are economically produced and assembled.

Objects relating to details and economies of the invention will appear from the description to follow. The invention is defined and pointed out in the claims. A preferred embodiment of the invention is illustrated in the accompanying drawing, in which:

FIG. 1 is a fragmentary vertical section of a window assembly embodying the invention, with the window open.

FIG. 2 is an enlarged fragmentary view corresponding to that of FIG. 1 with the window in closed position and the regulator being in fully retracted position.

FIG. 3 is a plan or top view of the regulator in operative relation to a window sill and sash, fragments of which are shown, the window being sectioned on a line corresponding to line 3—3 of FIG. 2.

FIG. 4 is a fragmentary view of the parts illustrated in FIG. 3, with the window in open position.

FIG. 5 is an enlarged fragmentary view partially in section on a line corresponding to line 5—5 of FIG. 3.

FIG. 6 is an enlarged fragmentary plan view, the parts broken away to show structural details.

FIG. 7 is a fragmentary view mainly in section on a line corresponding to broken line 7—7 of FIG. 6.

FIG. 8 is a fragmentary view, partially in section on a line corresponding to line 8—8 of FIG. 7.

FIG. 9 is a fragmentary plan view of the base member of the support.

FIG. 10 is an elevational view of the base member of the support.

FIG. 11 is a fragmentary perspective view illustrating details of the sash attaching bracket and the connection of the links thereto.

FIG. 12 is a view in section on a line corresponding to line 12—12 of FIG. 11.

FIG. 13 is a fragmentary elevational view of a window sash with the regulator attaching bracket mounted thereon.

In the accompanying drawing, we have illustrated the invention as applied to a window of the awning or horizontally swingable type, that is, one which is hingedly mounted at its upper edge. It is desired to point out, however, that regulators embodying the invention are well adapted for use in various types of windows, ventilators, and the like. It is particularly desirable for use in connection with windows owing to the fact that it is

2

compact and attractive in appearance, and is very easily operated.

The embodiment of the invention illustrated comprises a support including the base member 1 and top member 2 which coat to provide a housing for certain of the operative parts. The base member 1 is desirably formed of sheet metal stock and has upwardly offset laterally spaced arm supporting portions 3, its end portions 4 being adapted to be secured to a window sill or other support as 5 by screws or other suitable fasteners 6, holes 7 being provided for the fasteners. The top member 2 has a central upwardly offset portion 8, its end portions 9 being disposed in parallel relation to the portions 3 of the base. The headed actuating arm bearing members 10 also serve as rivets connecting the support members, the members 10 being provided with shoulders 11 and having upset portions 12, as is illustrated in FIG. 7.

The base member 1 is provided with upturned flange-like bearing members 13 having bearing openings 14 therein for the shaft 15 of the worm 56 which is disposed between the base and top members of the support and between these bearing members 13. The bearing members 13 have lug-like extensions 16 on their upper edges which engage holes 17 provided therefor in the top support member. These features are clearly illustrated in FIGS. 6 to 9 inclusive.

The worm shaft 15 is provided with a socket 18 for the operating crank 19 which may, if desired, be secured in the socket as by means of the screw 20. The upset portions 3 of the base member provide supports for the arms 21 which are desirably formed as stampings and have enlarged portions at their inner ends provided with toothed segments 22 coacting with the worm. These arms are swingably mounted on the members 10 and are supportedly and swingably disposed between the top and base members of the support. The relationship of these parts is clearly illustrated in FIGS. 6 and 7.

The arms 21 have angularly disposed upwardly projecting outer end portions 23 having openings 24 therein adapted to receive the reduced portions of the pivots 25 which connect the links 26 to the arms. The links 26 have laterally projecting outer end portions 37 which terminate in the angularly disposed end portions 27 which are angled to correspond to the angularly disposed end portions 23 of the arms 21 and are provided with pivot holes 28 for the pivots 25 carried by the arms, see FIG. 5. These pivots 25 are shouldered so that in assembling the arms and links are not clamped together when the pivots are upset at 29, see FIGS. 3, 4, and 5. The links 26 are connected to the sash attaching bracket 30 which is provided with longitudinally spaced sets of hinge knuckles 31 adapted to receive the hinge pins 32 which connect the coupling members 33 to the bracket, the coupling members having interengaging hinging pin receiving knuckles thereon. The links are detachably secured to the coupling members 33 by means of the pivots 34 which are desirably of the springable or snap fastener type illustrated. These pivots 34 are secured to the coupling members 33 by means of the clamping ears 35, see FIG. 12. The links 26 are provided with holes 36 which have snap-on engagement with these springable pivots 34.

The laterally projecting end portions 37 in the links 26 result in several advantages, among them being that they permit the links and the arms being collapsed into substantially parallel and in partially overlapping relation as is illustrated in FIG. 3. Also, when the crank is

operated to open the sash there is a direct application of force through the offsets 37 which is highly effective, that is, there is leverage action and even a sash which has adhered thereto by paint may be frictionally engaged with frame parts or the leverage is such that the window may be forced open and this without damage to the mechanism.

The actuating arms 21 are relatively thick as compared to the links 26 as is illustrated in FIG. 5, so the arms do not bend under any ordinary stress. The links are designedly relatively flexible and that is desirable because the bottom of the sash or other closure raises as it is swung outwardly. The pivotal connection for the links with the sash avoids subjecting the connecting pivots to any undue stress.

The offsets 37 and the links 26 permit the links and arms to collapse into partially overlapping relation as illustrated in FIG. 3, and with the sash attaching member 30 in parallel relation to the links and arms. This not only provides for compact collapsing but it insures effective operation from the collapsed position. The upturned or upwardly inclined outer ends of the arms 21 and the corresponding angular ends of the links 26 permit the upward swinging of the sash when it moves outwardly without substantial stress on the pivots. This also readily adapts the structure to installation in which the windows are supported so the top moves or swings downwardly as the window is opened. The detachable connections for the links to the sash is of advantage in that it permits manipulation of the window for washing, for example, as well as being an advantage in assembling and installing.

In the accompanying drawing we have illustrated our invention as embodied in a window of this type comprising a frame 39, the window being hinged to the top of the casing at 40.

The details of the frame form no part of the invention and are, therefore, not described. The window illustrated is of a well-known and widely used type. The sash attaching bracket 30 is adapted to receive a plurality of attaching screws at 41 and is positioned on the inner side of the bottom rail of the sash. The operator is desirably assembled as a unit and may be readily attached in operative relation to the window sill or other portion of the frame, and the bracket attached to the sash or other part operated. However, if desired the links may be readily disengaged from the pivot studs 34 to facilitate installation or cleaning of the window, and reengage therewith as occasion may require.

The parts of the operator of the invention may be very economically produced and assembled. The structure is simple and compact, and with the offsets 37 of the links the operator is very compact when the parts are in a retracted position. The operator is very easily operated. The worm acts or serves as a lock for retaining the parts in their adjusted position.

We have illustrated and described the invention in a highly practical embodiment thereof. We have not attempted to illustrate or describe other embodiments or adaptations, as it is believed that this disclosure will enable those skilled in the art to embody or adapt the invention as may be desired.

Having thus described the invention, what is claimed as new and is desired to be secured by Letters Patent is:

1. In a window operator, a support comprising a base support member adapted to be superimposed upon a window sill or the like and having front and rear centrally positioned flange-like bearing members projecting upwardly from its front and rear edges, said bearing members having upwardly projecting lugs on their upper edges, said base support member having upwardly offset actuating arm seats disposed one at each side of its said bearing members, a top support member disposed upon said base support member and having slots therein receiving said lugs on said bearing members and having downwardly offset portions disposed in vertically spaced

relation to said arm seats on said base member, an actuating worm disposed above and transversely of said base member and between and journaled in said bearing members thereon, said base and top support members and said bearing members constituting a housing for said worm, bar-like actuating arms of flat section having toothed segments on their inner end edges coacting with said worm, and pivots for said arms disposed through said base and top support members, said pivots being shouldered at their inner ends to supportedly engage said base support member and headed at their outer ends to retainingly engage said top support member and constituting connecting rivets for said support members.

2. In a window operator, a support comprising a base support member adapted to be superimposed upon a window sill or the like and having front and rear centrally positioned spaced bearing members projecting upwardly therefrom, said base support member having actuating arm seats disposed one at each side of its said bearing members, a top support member disposed upon said base support member and having portions disposed in vertically spaced relation to said arm seats on said base member, an actuating worm disposed above and transversely of said base member and between and journaled in said bearing members thereon, actuating arms having toothed segments at their inner ends disposed on opposite sides of and coacting with said worm, pivots for said arms disposed through said base and top support members, an elongated sash attaching bracket having laterally spaced coupling members pivotally mounted thereon with their pivots in axial alignment, and coupling links pivotally connected to the outer ends of said actuating arms and to said attaching bracket coupling members.

3. In a window operator, a support comprising a base support member adapted to be mounted on the upwardly facing surface of a window sill or the like and having opposed centrally positioned spaced bearing members projecting upwardly therefrom, said base support member having actuating arm seats disposed one at each side of its said bearing members, a top support member disposed upon said base support member and having portions disposed in vertically spaced relation to said arm seats on said base member, an actuating worm disposed between and journaled in said bearing members, bar-like actuating arms of flat section having toothed segments on their inner end edges coacting with said worm, pivots for said arms disposed through said base and top support members, said arms having angularly disposed upwardly projecting portions at their outer ends, coupling links pivotally connected to the said upwardly projecting outer ends of said actuating arms, the ends of said links connected to said arms being offset edgewise and having terminal portions disposed at angles corresponding to the angled ends of said arms and lappingly disposed thereon, said offsets in said links being such as to permit the links to lie in substantially parallel and partially overlapping relation to the arms when the arms are in fully retracted position, and a strap-like sash attaching bracket provided with spaced pivoted link coupling members to which the outer ends of said links are pivotally connected, said bracket being substantially parallel to said arms and links when the arms are in fully retracted position.

4. In a window operator, a support, an actuating worm journaled on said support, actuating arms of flat section pivotally mounted on said support and having toothed segments coacting with said worm, said arms having angularly disposed upwardly projecting portions at their outer ends, coupling links pivotally connected to the said upwardly projecting outer ends of said actuating arms, the ends of said links connected to said arms being offset edgewise and having terminal portions disposed at angles corresponding to the angled ends of said arms and lappingly disposed upon and pivotally connected thereto, said offsets in said links being such as to permit the links to lie substantially parallel to said arms when the arms and links

are in fully retracted position, and a sash attaching bracket provided with spaced pivoted link coupling members to which the outer ends of said links are pivotally connected, said bracket being substantially parallel to and closely adjacent said arms and links when the arms 5 and links are in fully retracted position.
